UNITED STATES PATENT OFFICE.

DAVID SPENCE, OF NORWALK, CONNECTICUT, ASSIGNOR TO THE NORWALK TIRE AND RUBBER COMPANY, OF NORWALK, CONNECTICUT, A CORPORATION OF CONNECTICUT.

DESIGN FOR A TIRE-TREAD.

50,431.

Specification for Design.

Patented Mar. 6, 1917.

Application filed December 11, 1916. Serial No. 136,341. Term of patent 14 years.

To all whom it may concern:

Be it known that I, DAVID SPENCE, a subject of the King of Great Britain and Ireland, residing at Norwalk, in the county of Fairfield, State of Connecticut, have invented a new, original, and ornamental Design for a Tire-Tread, of which the following is a specification, reference being had to the accompanying drawing, forming a part thereof.

Figure 1 is a plan view of a design for a tire tread.

Fig. 2 is a miniature perspective view of a tire having thereupon a tread which embodies the design shown in Fig. 1.

Copies of this patent may be obtained for five cents each, by addressing the "Commissioner of Patents, Washington, D. C."

Fig. 3 is a partial transverse section taken as on the line 3—3 of Fig. 2 looking in the direction of the arrows. In Fig. 1 the tread design is shown flattened or extended, as will be noted from a comparison of Figs. 1 and 3.

I claim as new—

The ornamental design for a tire tread as shown.

DAVID SPENCE.
